Primary Examiner — Abraham Bahta(74) *Attorney, Agent, or Firm* — Pacifica IP(57) **CLAIM**

The ornamental design for a hanger spacer tape, as shown and described.

DESCRIPTION

FIG. 1 is a front perspective view of the hanger spacer tape in a coiled state;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right-side view thereof;

FIG. 8 is a perspective view of a portion of the hanger spacer tape of FIG. 1 in use;

FIG. 9 is a top view thereof;

FIG. 10 is a bottom view thereof;

FIG. 11 is a right-side view thereof; and,

FIG. 12 is a left side view thereof.

The broken lines in the drawings are for illustrative purposes only and do not form part of the claimed design.
